UNITED STATES PATENT OFFICE.

CHARLES E. STELLER, OF MILWAUKEE, WISCONSIN.

DOOR-KNOB ATTACHMENT.

SPECIFICATION forming part of Letters Patent No. 410,216, dated September 3, 1889.

Application filed April 8, 1889. Serial No. 306,392. (Model.)

To all whom it may concern:

Be it known that I, CHARLES E. STELLER, of Milwaukee, in the county of Milwaukee and State of Wisconsin, have invented new and useful Improvements in Door-Knob Attachments; and I do hereby declare the following to be a full, clear, and exact description of said invention, reference being had to the accompanying drawings, and to the letters or figures of reference marked thereon, which form a part of this specification.

My invention relates to improvements in door-knob attachments; and it pertains more especially to the peculiar construction of the device by which the knob-shank is secured to the spindle, and the construction of my improvement is explained by reference to the accompanying drawings, in which—

Figure 1 represents a perspective view of my device attached to a door. Fig. 2 is a longitudinal vertical section through the knob and shank, showing therein a side view of the spindle and the cam-lever by which it is connected with the shank. Fig. 3 is a rear view of the knob and retaining-plate with the rose removed.

Like parts are represented by the same reference-letters throughout the several views.

A A are door-knobs, which are secured to the respective sides of the door B upon the respective ends of the spindle C.

D is an ordinary rose, which is used to cover up from view the fastening device and give it a finished appearance. The fastening device consists in a cam-lever E, which is pivoted eccentrically to the end of the shank F upon the pivot or screw G, which pivot or screw G passes through an aperture formed therefor in said cam-lever E, and is rigidly affixed at its inner end to the end of the shank F. A series of notches I I are formed in the surface of the spindle C, preferably at one of its corners, for the reception of the cam-lever E. The eccentric bearing of the cam-lever is so formed as when in the closed position to be brought directly in line between one of the notches I and the retaining-pivot G, whereby such eccentric bearing of said cam-lever E acts as a wedge between the pivot G and one of the retaining-notches I, and consequently as said cam-lever E is turned downward from the vertical position shown in Fig. 3 against the spindle, as indicated by dotted lines in said figure, the eccentric bearing of said cam-lever acts as a wedge and

presses with great force against said spindle, whereby said spindle is held rigidly in place in its retaining-socket within the shank F, and all tendency to rattle or shake upon the spindle is thereby obviated, and the cam-lever is retained rigidly in place in its locking position by reason of its intense pressure against the side of said spindle, whereby the shank is more rigidly secured to the spindle than by the locking devices as heretofore constructed, and all liability of the knob-shank becoming disengaged is thereby obviated. To provide for attaching the cam-lever E to shanks of small diameter, an upward-projecting flange H is formed integral with said shank for the reception of the pivot G. The swinging arm of the cam-lever E is so shaped that when engaging in one of the notches of said spindle it is brought beneath the periphery of the shank or retaining-flange H; but when desirous to disengage it from the spindle it is turned on its retaining-pivot until its retaining-edge is disengaged from the spindle, as shown in Fig. 3. It is obvious that as the eccentric bearing-surface of said cam-lever engages in the retaining-notch directly in line between said notch and the retaining-pivot any strain brought to bear upon said spindle has no tendency whatever to turn said eccentric upon its supporting-pivot. A thin washer is preferably located between the end of the pivot G and the door to prevent the surface of the door from becoming worn by contact with the fastening.

Having thus described my invention, what I claim as new, and desire to secure by Letters Patent, is—

In a door-knob attachment, the combination, with the knob-shank F and spindle C, provided with a series of retaining-notches I, of the cam-lever E, pivoted eccentrically to said shank F, the eccentric bearing of said cam-lever being located between the cam-supporting pivot and the retaining-notches of said spindle, and adapted to engage in one of the notches of and act as a wedge between the retaining-pivot and said spindle, substantially as and for the purpose specified.

In testimony whereof I affix my signature in presence of two witnesses.

CHARLES E. STELLER.
